(57) **CLAIM**

I claim the ornamental design for a dish rack, as shown and described.

DESCRIPTION

FIG. 1 is an isometric top, right side view of a dish rack; FIG. 2 is a top view thereof;

FIG. 3 is a bottom view thereof;

FIG. 4 is a front view thereof;

FIG. 5 is a right side view thereof;

FIG. 6 is a rear view thereof;

FIG. 7 is a left side view thereof;

FIG. 8 is an enlarged view of section A of FIG. 7;

FIG. 9 is a sectioned elevation left side view thereof, the section being taken in a direction of section line 9--9 of FIG. 2;

FIG. 10 is a sectioned elevation left side view thereof, the section being taken in a direction of section line 10--10 of FIG. 2;

FIG. 11 is a sectioned elevation left side view thereof, the section being taken in a direction of section line 11--11 of FIG. 2;

FIG. 12 is an isometric top, right side view of a second embodiment of a dish rack, the second embodiment of a dish rack having a number of like features of the dish rack of FIG. 1, and replicate the same views as FIGS. 4, 5, 6, 7; 8, 9, and 10;

FIG. 13 is a top view of the second embodiment thereof; and,

FIG. 14 is a top view of the second embodiment thereof. The broken lines in the drawings depict portions of the embodiments of the dish rack form no part of the claim.
